UNITED STATES PATENT OFFICE.

ALFRED L. WEISSENTHANNER, OF NEW YORK, N. Y.

RECEPTACLE-CLOSURE.

No. 857,698.

Specification of Letters Patent.

Patented June 25, 1907.

Application filed November 15, 1905. Serial No. 287,451.

To all whom it may concern:

Be it known that I, ALFRED L. WEISSENTHANNER, a citizen of the Republic of France, and a resident of New York city, State of New York, have invented a certain new and useful Improvement in Receptacle-Closures, of which the following is a specification.

In that type of sealing cap comprising a pendent flange adapted to be bent into locking engagement with the shoulder on the head of a bottle or jar some kind of packing or cushioning medium has been universally employed. This medium in the form of a flat disk of elastic material is placed within the cap and by pressure applied to the top of the cap, while the bottle is firmly supported, is compressed and made to conform to the lip of the bottle or jar. The flange of the cap is then bent, by means of a suitable machine, into locking engagement with the shoulder on the bottle or jar for the purpose of holding the disk under compression to maintain an effective seal. Cork by reason of its lightness and elasticity is peculiarly adapted to this purpose and has been extensively used. The cork-wood from which the disks are cut is not of uniform structure throughout its mass even with the highest grades, in consequence of which many disks after being cut are found to be worthless and incapable of use by reason of the presence of numerous cells which would prevent effective sealing. These imperfect disks must necessarily be discarded, entailing thereby in the aggregate an enormous loss to the bottler or the manufacturer of the sealing caps. Notwithstanding this condition however the use of cork for this purpose still persists, although many substitutes have been suggested therefor, notably rubber or compositions thereof.

It is one of the essential objects of the present invention to devise a closure whereby cork of any quality, provided it possesses the necessary elasticity, and of any condition of cellular structure may be employed.

My invention in its broadest aspect consists of a sealing disk of elastic material capable of being compressed to the requisite degree to make an effective seal, and a facing of flexible and preferably inelastic material which has the capability of being bent to conform to the rim of the bottle or jar and of

such nature as to be in itself substantially impervious to fluids or made so by a suitable coating. As the elastic medium I prefer cork on account of its cheapness and adaptability to the intended purpose and its effectiveness in making a tight seal. As the facing medium I have used what is known as "fiber", a well known insulating material, and also pasteboard.

The invention will be understood by reference to the accompanying drawing in which

Figure 1 is a central vertical section of a cap having the sealing disk in position before being applied to the bottle or jar; Fig. 2 is a view partly in section of the neck of a bottle showing the cap after the sealing operation; Fig. 3 is a perspective view of the facing or lining disk; and Fig. 4 is a plan view of a defective cork disk for the purpose of illustrating its cellular structure.

Similar reference numerals indicate similar parts in the several views.

Referring to the drawings the numeral 1 designates the neck of a bottle which has formed thereon a shoulder 2 at or near the head, the term "bottle" being here used in its broadest significance to designate a receptacle designed to contain liquids, preserves, meats, etc.; 3 designates a cap of sheet metal which may be of any of the usual forms known to the trade. As here shown it comprises a flat crown or top portion 4 having an integral depending circumferential flange 5, the latter being adapted to be bent into locking engagement with the shoulder 2. It is to be understood that I have selected this type of cap simply for the purpose of illustration, the invention being adapted to caps having either plain, corrugated or split flanges, and to caps having the flange separate from the crown, all of which types are well known.

The sealing disk, which constitutes the essential feature of my invention, comprises a disk 6 of any suitable elastic material, preferably cork, of a diameter substantially equal to the diameter of a section through the flange 5 so that it will rest snugly within the cap. In practice such disks for use in connection with caps for bottles containing beer or carbonated beverages are cut about one inch in diameter and about one-tenth of

an inch in thickness, the diameter and thickness varying in accordance with the particular size of the bottle or jar with which the cap is to be used. Against the elastic disk 6 is placed 5 a disk 7 of flexible and preferably inelastic material having the capability of being bent at the time of compression of the disk 6 to conform to the rim of the bottle. As an example of a material suitable for the purpose I have 10 used "fiber", which as above stated is a well known insulating material, and which in itself is substantially impervious to fluids, of a dense texture, very tough and innocuous, characteristics which adapt it to the present 15 purpose. The disks 7 are cut from sheets the same diameter as the cork disk 6 and about one-fiftieth of an inch in thickness, although they may be of greater thickness if desired. I have also used pasteboard but when that or 20 a similar material is used it must be treated to render it practically tasteless and odorless to prevent any contamination of the contents of the bottle or jar. For that purpose I coat one face of the pasteboard disk with 25 any suitable innocuous substance, linseed oil having in practice been found suitable for that purpose. The pasteboard disk may be prepared in any suitable manner for this coating, the oil when hardened presenting 30 a practically smooth continuous surface 8 closing the pores of the pasteboard and rendering it impervious to water, gases or other fluids which may be in the containing bottle or jar.

35 The fiber disks may be used in their natural state, that is as found upon the market and without any special preparation, as by reason of its very dense texture it is for all practical purposes as a sealing medium impervious 40 to water or other fluids. Said disks, however, may have a coating of linseed oil the same as pasteboard disks if deemed necessary or desirable.

When a bottle is to be sealed the elastic 45 section or disk 6 is placed within the cap and the inelastic section or disk 7 superposed thereon as indicated in Fig. 1. By means of any well known machine vertical pressure is applied to the top of the cap by which the 50 disk 6, which is normally flat, is compressed about its edge and made to conform to the lip of the bottle. The disk 7 being inelastic and incompressible, but flexible, will be bent into like conformity with the rim of the bottle. While this pressure is being maintained 55 a flange bending tool is brought into operation to bend the flange 5 of the cap 3 into locking engagement with the shoulder 2, as indicated in Fig. 2. After the completion of 60 the sealing operation the sealing disk will be maintained under compression and capable of resisting any internal pressure.

In Fig. 4 I have shown on a slightly en-

larged scale the cellular structure of a cork disk selected from among those cut for commercial use. This disk, it will be noted, is pitted with cells 9 which extend through from face to face particularly over the surface that is compressed in the sealing operation. Such disk is absolutely valueless when used 65 alone as a sealing medium, and is typical of disks by which effective sealing cannot be effected and which must therefore be rejected, the aggregate loss therefrom representing 70 a very large money value, not only for material but labor in preparing and cutting. The disk 7 while it may be advantageously employed with perfect cork disks is more particularly intended for use by me with corks, which by reason of imperfections above 75 noted, have heretofore been discarded, or in other words with cork disks which are incapable of being used alone. The disk 7 may if desired be cemented to the face of the cork disk but that is not necessary for its successful use. When laid upon the face of an imperfect disk, such as illustrated in Fig. 4, the 80 cells 9 are closed, in-as-much as the impervious disk 7 prevents the escape of gases or liquids contained in the bottle or jar and the 85 seal will be maintained in as reliable and effective condition as with a perfect cork disk.

One of the essential advantages of "fiber" and pasteboard as materials for the disks 7 is that they possess the necessary density and 90 rigidity to withstand any internal pressure which would tend to break or bend them at the points where they cover the cells 9 of an imperfect cork disk 6. The utility of the 95 present sealing disk has been fully demonstrated in practice, enabling the practical utilization of cork disks of the character illustrated in Fig. 4 which, as above stated, have heretofore been rejected.

My invention in its broader aspect is not 105 limited to the precise forms of construction and disposition of the parts shown herein as changes in structure and disposition other than those herein suggested may be made without departing from the main purpose of 110 my invention or without sacrificing its chief advantages.

What I claim and desire to secure by Letters Patent is:—

1. A sealing disk for the purpose described 115 comprising a section of an elastic material, and a superposed section of a stiff, flexible, inelastic, nonmetallic material, made impervious to fluids.
2. A sealing disk for the purpose described 120 comprising a section of an elastic material and a superposed section of a flexible but inelastic material, the latter having a coating of dried linseed oil.
3. A sealing disk for the purpose described 125 comprising a section of an elastic material

and a superposed section of pasteboard, the latter having a coating of dried linseed oil.

4. A sealing disk for the purpose described comprising a section of cork, and a superposed section of pasteboard, the latter having a coating of dried linseed oil.

In witness whereof I have hereunto signed

my name in the presence of two subscribing witnesses.

ALFRED L. WEISSENTHANNER.
